UNITED STATES PATENT OFFICE.

NILS P. BOLIN, OF BROCKTON, MASSACHUSETTS, ASSIGNOR OF ONE-HALF
TO WILLIAM G. SMITH, OF BROCKTON, MASSACHUSETTS.

DEVICE FOR DETACHABLY SECURING RUBBER HEELS TO BOOTS AND SHOES.

No. 811,365.

Specification of Letters Patent.

Patented Jan. 30, 1906.

Application filed August 31, 1904. Serial No. 222,807.

To all whom it may concern:

Be it known that I, NILS P. BOLIN, a citizen of the United States, and a resident of Brockton, in the county of Plymouth and State of Massachusetts, have invented certain new and useful Improvements in Devices for Detachably Securing Rubber Heels to Boots and Shoes, of which the following is a specification.

This invention relates to a device for detachably securing rubber heels to boots and shoes; and it consists of a sheet-metal plate having prongs for securing it to the heel portion of the under sole of the boot or shoe, and a sheet-metal clasp embedded in the rubber heel and having guide-ribs adapted to be detachably secured to the side edges of the sole-plate, as will hereinafter be more fully shown and described, reference being had to the accompanying drawings, wherein—

Figure 1 is a perspective view showing the sole-plate and heel-clasp interlocked. Fig. 2 is a bottom plan view of the under sole of the boot and the pronged metal plate secured thereto. Fig. 3 is a bottom plan view of the metal clasp embedded in the rubber heel, which latter is represented in dotted lines. Fig. 4 is a sectional view on the line 4-4 in Fig. 2, showing the rubber heel attached to the sole of the boot or shoe; and Fig. 5 is a cross-section on the line 5-5 in Fig. 2, showing likewise the rubber heel attached to the sole of the boot or shoe.

Similar letters refer to similar parts wherever they occur on the different parts of the drawings.

In the drawings, A represents the heel portion of an outer side of a boot or shoe A', as usual. B is the rubber heel adapted to be secured to said heel in a detachable manner. In connection with the leather sole I use a skeleton sheet-metal plate C, provided with a series of upwardly-projecting prongs C' C'' or nails driven in plate on sole and adapted to be driven through the shoe-sole and firmly clenched thereto. Intermediate the bases of said prongs are ribs C'' on the metal plate C for limiting the latter from being driven closely in contact with the under side of shoe-sole for a purpose as will be further described. In one piece with the rear end of the plate C is a tongue C³, terminating as a hooked locking projection C⁴, adapted to be yieldingly interlocked with a curved tongue D³, forming

a part of a skeleton sheet-metal clasp composed of curved lateral cross-bars D D, adapted to be embedded and concealed in the rubber heel B, as shown, while the latter is in a plastic condition. Integral with said cross-bars D are made metal hooked guide-bars D' D', adapted to receive the edges of the plate C, which is attached to the shoe-sole.

In operating this device the plate C is secured to the under side of the boot or shoe heel by the prongs C', as above described. Within the body of the rubber heel B is embedded, while it is in a plastic condition, the curved metal ribs D D, as well as a portion of the upper guide-bars D' D'. The rubber heel thus constructed is locked onto the plate C simply by sliding the guide-ribs D', which are attached to said rubber heel, into interlocking position relative to said plate C on the sole A until the end of the prong D³ is interlocked with the hooked projection C⁴ on the end of the plate C, as represented in Fig. 1. By this arrangement the rubber sole is firmly secured to the sole of the boot or shoe.

The rubber heel may readily be removed simply by inserting a thin metal bar, small screw-driver, &c., between the ends of the tongues C³ D³, by means of which the latter may be pried apart sufficiently to disengage the metal plates C D, after which the rubber heel can readily be withdrawn, changed from one shoe to another, or replaced by a new one, as may be desired.

By having ribs C'' on the upper side of the pronged plate C intermediate the prongs C' the said plate is prevented from being driven in close contact with the sole, so as to leave a space for receiving the hooked guide-bars D', attached to the rubber heel.

At the ends of the skeleton plate C are side projections C⁵ C⁶ to serve as stops against the ends of the guide-bars D' D' when the rubber heel is moved to its proper normal position. (Shown in Fig. 4.)

What I wish to secure by Letters Patent and claim is—

1. A heel-section for a boot or shoe having a plate composed of curved lateral cross-bars embedded therein and having its side edges bent inwardly to form guideways, combined with a companion plate carrying a plurality of upwardly-projecting prongs, secured to the bottom of the boot or shoe, same adapted to be slidably engaged by the first-mentioned

- plate, and each of said plates having yieldable extensions, the terminals of which are bent to interlock and prevent the movement of the last-mentioned plate in one direction.
- 5 2. A heel-section for a boot or shoe having a plate embedded therein with the side edges bent to present guideways, combined with a companion plate carrying a plurality of prongs, secured to the bottom of the boot or shoe, same adapted to be slidably engaged by the first-mentioned plate, each of said plates having yieldable extensions, said members being bifurcated, two opposing branches of the bifurcation being yieldably interlocked, and the other two opposing branches being outwardly divergent to present an opening for the reception of an implement to separate the interlocked branches.
- 10 3. A heel-section for a boot or shoe having a plate embedded therein with its side edges bent to present guideways, combined with a

companion plate carrying a plurality of prongs, secured to the bottom of the boot, same adapted to be slidably engaged by the first-mentioned plate, each of said plates having yieldable extensions, said members being bifurcated, two opposing branches of the bifurcation being yieldably interlocked, and the other two opposing branches being outwardly divergent to present an opening for the reception of an implement to separate the interlocked branches.

In testimony whereof I have affixed my signature in presence of two witnesses.

NILS P. BOLIN.
